COMBINED TEMPERATURE CONTROL PANEL AND CLOCK

Henry Dreyfuss, South Pasadena, Calif., assignor to
Minneapolis-Honeywell Regulator Company, Minne-
apolis, Minn., a corporation of Delaware

Application November 10, 1955, Serial No. 38,823

Term of patent 14 years

(Cl. D52—7)

The figure is a perspective view of a combined temperature control panel and clock, looking from below and to the right, showing my new design.

I claim:

The ornamental design for a combined temperature control panel and clock, substantially as shown.
